UNITED STATES PATENT OFFICE

2,193,030

HAND BRAKE MECHANISM FOR RAILWAY CARS

John A. Leiedecker, St. Louis, Mo., and Jacob A. Hyle, Chicago, Ill., assignors, by mesne assignments, to Champion Brake Corporation, Wilmington, Del., a corporation of Delaware

Refiled for abandoned application Serial No. 748,408, October 15, 1934. This application May 26, 1936, Serial No. 81,974

5 Claims. (Cl. 254—149)

This invention pertains to special and improved means for locking and releasing the hand brake shaft employed in connection with hand brakes for railway cars, including novel means for quickly taking up the slack and applying the required power safely in properly applying the brakes. This application is refiled for our abandoned application Serial No. 748,408, filed October 15, 1934.

10 The prime object of the invention is to provide novel, simple, safe, durable, economical, and thoroughly practical and efficient brake mechanism for effectively and quickly applying and releasing said mechanism.

15 Another object of the invention is to so construct our improved mechanism that it may be readily, easily, economically, and quickly applied to any and all types of cars with which the ordinary hand brakes are now commonly utilized.

20 Further objects of the invention are to so construct our novel means that it may at an economical cost be installed on freight cars so as to replace the usual type of braking and releasing mechanism; that it will freely and safely operate under any and all conditions of the climate; that the operating parts are fully and properly protected from snow, rain, ice, and sleet and thereby prevents undue accumulation of snow and ice which has been known to cause serious interference with the practical operation of the several parts of the mechanism employed, resulting in costly and serious damage; that the use of any and all types of springs are entirely dispensed with; that the parts are so constructed, assembled, arranged, and disposed as to prevent any accidental disarrangement or disconnection of parts by the ordinary usage to which railway freight cars are usually subjected; that in the event that any part or member of said improved means shall have accidentally become broken, impaired, or damaged, said part or member may be easily removed and a new one readily substituted therefor.

The foregoing and such other objects as may appear from the ensuing description are accomplished by the construction, arrangement, combination, and location of the several parts hereinafter more fully described and illustrated in the accompanying drawing and more particularly pointed out in the claims appended hereto, it being understood that slight changes in the precise shape, proportions, and minor details of the construction may be resorted to without departing from the spirit or sacrificing any of the advantages of the invention.

In the accompanying drawing forming a part of this specification, it will be seen that:

Fig. 1 is a front elevation of the improved mechanism embodying our invention;

Fig. 2 is a vertical section taken in the plane 5 of the dotted lines 2—2, Figure 1, looking in the direction of the arrows;

Fig. 3 is a central vertical section taken in the plane of the dotted lines 3—3, Fig. 1; and

Fig. 4 is a transverse section taken through 10 the casing showing the operating parts partly in section and partly in elevation, and showing the main brake operating chain wheel shifted from the position such as is shown in Fig. 3.

In the embodiment of our invention as illustrated, it will be seen that a casing for enclosing and protecting the operating parts is provided, said casing being formed of two pieces of suitable plate metal, designated by the numerals 1 and 2, each of said plates having a lateral extension at each side, and are fixedly secured together by suitable securing means at 3, with openings 4 formed therethrough for the reception of suitable securing bolts for fixedly securing the casing to a car. Suitably secured and supported within the casing is the main operating shaft 5 which is provided with two integral collar members 6 adapted to rest in easy contact with the inner face of the casing at each side thereof and prevent any sidewise vibration or movement of 20 said shaft, the outer end of the shaft being provided with the usual hand operating wheel 7 fixedly secured to said shaft, while to the inner end portion of the shaft is fixedly secured a pinion 8 adapted to mesh with the main driving gear 30 wheel 9, and within the casing intermediate the shaft is fixedly secured a ratchet wheel 10, and rigidly secured to the outer face of the casing and surrounding the shaft 5 is a bearing and shaft supporting member 11 adapted to support the 35 weight of said shaft and operating wheel 7; to furnish an extended bearing surface for the shaft and to prevent excessive wear to the casing through which the shaft passes by the excessive jarring and vibration of the shaft and 40 wheel to which they are necessarily subjected.

Disposed above the shaft 5 and supported within the casing at one side of the shaft is another shaft 12, each end portion thereof being provided with suitable means for preventing sidewise shifting or movement, while to the outer end of the shaft 12 is suitably secured a handle member 13 for imparting a partial rotary movement to the shaft 12, and loosely pivoted to shaft 12 intermediate its length is a locking pawl 14, 50 55

and passing through two openings formed through said shaft 12 are the two vertical extended portions of a staple-like formation 15, each of its ends being riveted to the shaft 12, 5 while the depending horizontal portion of the formation 15 and the lowermost vertical portions thereof straddle the hub portion of the said pawl and serve to retain the pawl in proper alignment with the ratchet 10 under all conditions, said 10 pawl 14 being adapted to automatically ride over the ratchet wheel while applying the brake and to drop into locking engagement therewith when the brake shall have been suitably applied. When it is desired to release the brake, it is simply 15 necessary for the brakeman to reach the handle which projects upwardly overlapping the top portion of the casing and extended above said casing within easy reach and by imparting a suitable lateral swing to said handle will cause 20 a partial rotation of the shaft and cause the horizontal portion of the staple formation to contact with the lower face of the pawl 14, thereby disengaging the pawl from the ratchet 10 thereby 25 immediately releasing the brake.

25 Disposed within the casing below the main operating shaft 5 is the main chain operating wheel 9 formed from a single piece of metal formed with gear teeth around its peripheral portion, said drive wheel comprising a centrally 30 disposed shaft and hub portion 16, each reduced end portion of the shaft being fitted within the casing with a shouldered portion resting against the inner face of the casing to prevent any side- 35 wise movement of the wheel, and radiating from said hub portion is a plurality of spokes 17. To the outer end portion of one of the spokes is formed a lateral box-like extension 18 having an opening therethrough for the reception of the end link of the brake operating chain 19, 40 and formed integral with a portion of the inner face of the wheel 9 is a laterally extended member 20 inclined inwardly from the outer face of the extension 18 to the inner face of the peripheral portion of said wheel 9 for the purpose 45 hereinafter referred to. Formed integral with and intermediate of the shaft is an outward extension 20' with both its upper and its lower face gradually inclined outwardly and inwardly and terminating with a rounded end portion, being 50 in the form of a tapered pin or lug, and passing through one of the spokes 17 and its integral extension 18 is a pin 21 for loosely supporting the upper end link of the chain 19, said pin and extension having an opening formed there- 55 through for the reception of a suitable cotter pin 22 for removably retaining the pin 21.

60 By reference to Figs. 2 and 3 of the drawing, will be seen the position assumed by the parts of the mechanism when the brake is off, but, 65 when it is desired to release the locking pawl 14 from the ratchet wheel 10, impart a one-half turn of the operating wheel 7 to the right which will cause the slack to be taken up and cause the 70 chain operating wheel 9 to assume the position shown in Fig. 4, with the lower end portion of the end link of the chain riding the inclined portion of the extension 20' when further turning of the wheel 7 will cause said link to contact 75 with the shaft 16, and said action causing the second link to straddle said extension 20', simultaneously forcing the upper portion of the end link to rise slightly above the extension 18 on which it is loosely suspended by the pin 21, and the second link will be forced against said

shaft 16, thus transferring the strain from the end link to the second link, and the further movement of the hand wheel 7 causes the chain to ride over the outer facing the inclined lateral extension which forces the chain onto and to wind around the shaft 16 of compactively reduced diameter which imparts greater power to the braking action and thereby apply the brake with the desired power after the quick take-up of the slack. 10

It will be understood that the several parts of the mechanism employed in connection with our invention may be formed of any suitable dimensions and of any desired material possessing the required strength and durability required for 15 the practical purposes for which they are intended.

Having thus described our invention, what we claim and desire to secure by Letters Patent is:

1. In a brake operating mechanism of the 20 character described including a housing, a chain winding wheel mounted within said housing and means for operating the wheel, said wheel consisting of a single piece of metal formed with gear teeth around its peripheral portion, an enlarged hub portion and a reduced shaft member, a plurality of spokes radiating from the hub, a lateral extension formed on the outer end portion of one of the spokes for the reception of the end link of a chain, and an inclined lateral extension formed intermediate the shaft for the reception of the second link of the chain. 30

2. In a brake operating mechanism of the 35 character described including a housing, a chain winding wheel mounted within the housing and means for operating the wheel, said wheel consisting of a single piece of metal formed with gear teeth around its peripheral portion, an enlarged hub portion and a reduced shaft member, a plurality of spokes radiating from the 40 hub, a box-like extension formed on the outer end of one of the spokes with an opening therein for the reception of the end link of a chain, an inclined lateral extension formed intermediate the shaft for the reception of a second link of the 45 chain, and an inclined extension extending from said box-like extension to the peripheral portion of the wheel for forcing the chain outwardly onto the said shaft.

3. In a brake operating mechanism of the 50 character described including a housing, and means disposed within said housing for operating a chain winding wheel, said wheel consisting of a single piece of metal having an enlarged hub portion and a reduced shaft member, a 55 plurality of spokes radiating from the hub, a lateral extension formed at the upper end of one of the spokes adapted to receive the end link of a chain, a lateral extension formed on the shaft intermediate its length, said last named 60 extension being inclined inwardly and outwardly terminating with a rounded portion for the reception of the second link of the chain.

4. In a brake operating mechanism of the 65 character described including a housing, means mounted within the housing for operating a chain winding wheel, said wheel consisting of a single piece of metal formed with an enlarged hub portion and a reduced shaft member, a 70 plurality of spokes radiating from the hub, a lateral extension formed at the outer end of one of the spokes for the reception of the end link of a chain, an outward extension formed on the shaft intermediate its length, said last named 75 extension being inclined outwardly and termi-

nating with a rounded portion for the reception of the second link of the chain, and means passing through the first named extension for supporting the end link.

5. In a brake operating mechanism of the character described including a housing, a winding wheel mounted within the housing and a flexible winding member secured to said wheel, said wheel having a part upon which the winding member is wound by rotation of said wheel, a winding shaft for rotating said wheel, a ratchet wheel on said shaft and a pawl adapted to en-

gage the ratchet wheel, a pawl shaft rotatably mounted in said housing, said pawl being pivoted on said shaft, a staple fixed to the pawl shaft and straddling the hub of the pawl so as to properly align the pawl and to bear against the side of the pawl to lift it out of engagement with the ratchet wheel when the pawl shaft is rotated, and manually operable means for turning said pawl shaft.

5
